UNITED STATES PATENT OFFICE.

HERBERT LINDEMANN, OF HAMBURG, GERMANY, ASSIGNOR TO UEBERSEE GUMMIWERKE AKTIEN-GESELLSCHAFT, OF WANDSBEK, GERMANY.

DESIGN FOR AN INDIA-RUBBER BATH GLOVE.

Application filed October 13, 1924. Serial No. 11,051. Term of patent 3½ years.

To all whom it may concern:

Be it known that I, HERBERT LINDEMANN, a citizen of the German Realm, residing at Hamburg, in the country of Germany, have invented a new, original, and ornamental Design for India-Rubber Bath Gloves, of which the following is a specification, reference being had to the accompanying drawing, forming part thereof.

The figure is a plan view of an india-rubber bath glove showing my new design.

I claim:

The ornamental design for an india rubber bath glove as shown.

HERBERT LINDEMANN.
